(57) **CLAIM**

The ornamental design for a cat climber, as shown and described.

DESCRIPTION

FIG. 1 is a front perspective view of a cat climber showing our new design according to first embodiment;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is a front perspective view of a cat climber showing our new design according to the second embodiment;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top view thereof; and,

FIG. 16 is a bottom view thereof.

The evenly dashed broken lines show portions of the cat climber that forms no part of the claimed design. The cat climber is shown with a symbolic break in its height. The appearance of any portion of the article between the break lines forms no part of the claimed design.

1 Claim, 10 Drawing Sheets
